GAME TARGET UNIT

David H. Braun, Miami, Fla., assignor to All-Tech Industries, Inc., Hialeah, Fla., a corporation of Florida

Filed Apr. 19, 1962, Ser. No. 69,778

Term of patent 14 years

(Cl. D34—5)

FIG. 1

FIG. 1 is a perspective right side view of a game target unit, showing my new design.

FIG. 2 is a perspective left side view thereof.

The rear of the target portion is plain and unornamented.

The dominant features of the design are shown in full lines.

I claim:

The ornamental design for a game target unit, as shown and described.
